EMILIO GIAMPIETRO, OF LA FORMA, ITALY.

COMPOSITE PLUG FOR BOTTLES.

Application filed November 10, 1927, Serial No. 232,316, and in Italy November 17, 1926.

The present invention relates to a composite plug for bottles with the object to prevent that a bottle should be filled again with sophisticated or adulterated liquid and put on sale again thus surprising the good faith of purchasers.

The invention consists in providing the neck of a bottle with a plug composed of three parts, all three coaxial, of which the external 10 tubular shaped part is fixed within the bottle and cannot be extracted, while the two internal parts constituting a decomposable plug and united in any whatever way are separated from one another, when the bottle is 15 opened, the lower part falling down on the bottom of the bottle without any possibility of being united again to the upper one, or extracted, consequently revealing that the bottle has once been already opened, the upper 20 part being extracted as a usual plug.

The invention is schematically illustrated only by way of example in the drawing here-with annexed in which:

Fig. 1—shows a longitudinal section of a 25 bottle's neck, provided with a plug according to invention.

Fig. 2—shows a section on line $a-a$ of Fig. 1.

With reference to the figures: —1— is the 30 bottle's neck provided with a circular groove —2— at a certain height; —3— is the tubular part provided on its periphery with a groove —4— corresponding to groove 2, but with the concavity in opposite sense; —5— is an elastic 35 resistant metal ring; —6— is the cavity of the tubular part in which is tightly introduced a plug or stopper 7; —8— is a body of any convenient form fixed to the lower end 9 of the stopper member 7 in any practical or convenient 40 way, by means of soldering attrition, elastically and so on; —10— is a packing of rubber or other material which may secure the tight closing of the bottle.

The assembly and operation of the device 45 are as follows:

After insertion of the stopper 7 into the opening 6 of the tubular member, the member 8 is attached to the lower end 9 of said stopper and the packing ring 10 placed on the 50 periphery of the tubular member. The com-

plete plug thus assembled is then introduced into the neck of the bottle, the split resilient ring 5 being meanwhile compressed into the groove 4 in said tubular member until it arrives in alinement with groove 2 in the bottle 55 neck, whereupon the ring will expand into said latter groove and thereby permanently lock the tubular member against removal from the bottle neck. The bottle is thus hermetically sealed and may be put in commerce 60 filled with the liquid or substance whose sale is wanted to be protected.

Should the bottle be opened it is sufficient to extract the upper part of the decomposable plug —7—, the body —8— being then 65 separated from plug 7 and falling on the bottom of the bottle, while the liquid may flow through hole 6 of the tubular part 3.

It is clear that if the bottle should be filled again with liquid it would be impossible to 70 restore the plug to its original conditions so that any imitation or sophistication is prevented.

The practical form of the invention specified and illustrated by way of example may 75 of course be varied a great deal without trespassing the scope of the patent. Particularly shapes, dimensions and materials composing the different parts may be varied very much; the tubular part 3 and the part 7 may be for 80 instance of ground glass, the packing 10 and ring 5 may be of other substances different from those above specified.

Having now particularly described and ascertained the nature of my said invention 85 and in what manner the same is to be performed I declare that what I claim is:

1. The combination with a bottle, of a tubular member of rigid material seated in the neck of said bottle, means for preventing removal of said tubular member from the bottle without breakage, a stopper seated in said tubular member, and means carried at the inner end of said stopper and adapted to engage the inner end of said tubular member 90 and resist removal of the stopper, the organization being such that upon complete removal of said stopper the resisting means will remain in the bottle.

2. The combination with a bottle having 100

an internal annular groove in the wall of its neck, of a tubular member seated in said neck and having in its exterior periphery an annular groove registering with the neck groove, 5 a resilient metallic ring disposed in said grooves for permanently retaining said tubular member in said neck, a stopper seated

within said tubular member, and a stop member carried by said stopper below said tubular member and adapted to resist complete removal of the stopper. 10

In testimony whereof I have hereunto signed my name.

EMILIO GIAMPIETRO.
